UNITED STATES PATENT OFFICE.

FRED F. DENNIS, OF WORCESTER, MASSACHUSETTS.

METAL-PLANING MACHINE.

SPECIFICATION forming part of Letters Patent No. 335,744, dated February 9, 1886.

Application filed May 4, 1885. Serial No. 164,421. (No model.)

To all whom it may concern:

Be it known that I, FRED F. DENNIS, a citizen of the United States, residing at Worcester, in the county of Worcester and State of Massachusetts, have invented a new and useful Improvement in Metal-Planing Machines, of which the following is a specification, accompanied by drawings illustrating the features of my invention, and in which—

10 Figure 1 is a side elevation of a metal-planing machine. Fig. 2 is a top view of the driving-shafts, showing part of the frame in section. Fig. 3 is a side and detached view of a portion of the feeding mechanism. Fig. 4 is a 15 sectional view of a part of the feeding mechanism. Fig. 5 is an inside view of the feeding mechanism. Fig. 6 shows an inside view of the feeding mechanism similar to that shown in Fig. 5, except that the several parts are 20 represented at one end of their motion; and Fig. 7 shows the same view with the parts represented at the opposite end of their motion.

Similar letters refer to similar parts in the several views.

25 My invention relates to that portion of a metal-planing machine known as the "friction-feed," as hereinafter set forth and described.

The construction and operation of metal-planing machines are too well known to require 30 a detailed description. I have therefore herein confined myself specially to that portion forming the subject of my invention.

The several shafts shown in Fig. 2 have a 35 rotary motion in opposite direction as the two driving-belts $a a'$ are alternately transferred from the loose pulleys $b b$ to the tight pulleys $c c$ on the shaft d , and a reciprocating motion is thus given to the table B along ways upon the bed A by means of a rack (not shown) engaging the gear e , driven through intermediate gearing with the shaft d . Upon the shaft f , I attach a wheel, g , with a flange, g' , on its side, and having a reciprocating rotary motion as determined by the alternate action of the belts $a a'$.

40 Turning loosely upon the hub g^2 of the wheel g is a shell, h , having a hub, h' , with recesses $h^2 h'$, to receive the ends of the driving-dogs $k k$. The shell h , I hold in position by means of the collar h^3 , and upon the face of 45 the shell h , I attach the plate-wheel j with a slot, j' , carrying a stud, j^2 , which may be adjusted radially to vary the motion of the geared

rack j^3 , sliding in ways in the head of the planing-machine, and which actuates, through a pawl-and-ratchet device, a feed-screw, thereby 55 giving an intermittent motion to the cutting-tool in a manner familiar to all acquainted with machines of this class.

Within the shell h , I place the two driving-dogs $k k$, each having a transverse slot, k' , 60 inclosing the flange g' . The points k^2 of the dogs k rest in the recesses $h^2 h'$ and slightly in advance of a radial line passing through the point of contact of the dog k with the flange g' , as indicated by the broken line l . 65

The slots in the dogs are somewhat wider than the thickness of the flange g' , and to each dog I attach a spring, m , also attached to a pin or stud, n , in the shell h , the tension of the spring holding the dogs with the corners 70 $o o$ brought against the outer and inner surfaces of the flange g' .

When the motion of the wheel g is in the direction of the arrow 2, Figs. 5 and 6, the flange g' will be engaged by the corners $o o$ of 75 the right-hand dog, 5, as shown in Fig. 6, carrying the dog and shell h around in the direction of the arrows 2, Fig. 6, until the dog 5 is brought against a stationary pin, p , attached to the frame of the machine, and entering the 80 space between the flange g' and the outer rim of the shell h , thereby limiting the motion of the dog, its pressure against the pin p releasing it from its engagement with the rotating flange g' and stopping the motion of the shell h . 85

Whenever the rotary motion of the wheel g and shell g' is reversed, as indicated by the arrows 3, Fig. 7, the corners $o o$ of the left-hand dog, 6, as shown in Fig. 7, will engage the flange g' , and the motion of the shell h will 90 be reversed until the dog 6 is in turn brought against the fixed pin p , thereby limiting its motion, the pressure of the dog against the pin p releasing it from its engagement with the flange g' and stopping the motion of the 95 shell h .

Upon the inner side of the shell h , I place the projections q and q' , which, by the momentum of the shell, are brought against the dogs 5 and 6 as they are respectively 100 brought against the fixed pin p , thereby determining the exact limit of the motion of the shell h . It will thus be seen that, however long the rotary motion of the wheel g and

flange g' may be continued, the motion of the shell h and attached disk j will be limited to the distance between the two dogs $k k$, which I have in the present instance shown to be about one-third of the circumference of the shell h , but which may be varied, if desired.

By placing the dogs $k k$ on the lower side of the shell h , as shown in Fig. 5, the springs m m may be omitted or their tension reduced, as 10 the weight of the dogs will tend to press the corners $o o$ against the flange in position to immediately engage the same.

The contact of the dogs $k k$ with the wheel g and shell h is limited to the annular raised surfaces $r r'$, thereby reducing the friction and 15 the surface requiring to be finished.

What I claim as my invention, and desire to secure by Letters Patent, is—

1. The combination, with one of the shafts 20 of a metal-planing machine to which a rotary motion is alternately given in opposite directions by the action of the driving mechanism, substantially as described, of a wheel attached to said shaft and having an annular flange on

its side, a shell turning loosely and concentrically about said shaft, two dogs with their inner ends recessed in the hub of the shell, and having transverse slots forming corners adapted to engage the annular flange, and a pin attached to the frame of the machine and 25 entering the shell in the path of the outer ends of said dogs as they are carried around said shaft, all arranged and operating substantially as described, whereby the shell is given a rotary motion alternately in opposite directions, 30 but of limited extent, and means, substantially as described, whereby said shell is connected with the feeding mechanism, as and for the purpose set forth.

2. The combination, with the shaft f , carrying a wheel, g , having a flange, g' , of a shell, h , dogs $k k$, adapted to engage the flange g' , fixed pin p , and shell h , having projections q and q' , as and for the purpose set forth.

FRED F. DENNIS.
